Attorney

UNITED STATES PATENT OFFICE.

JOHN W. EDMANDS, OF NEWTON CENTER, MASSACHUSETTS, ASSIGNOR TO CENTRAL RAILWAY SIGNAL COMPANY, OF PITTSBURGH, PENNSYLVANIA, A CORPORATION OF NEW JERSEY.

RAILWAY SIGNAL-FUSEE.

1,103,278.

Specification of Letters Patent. Patented July 14, 1914.

Application filed May 5, 1914. Serial No. 836,582.

To all whom it may concern:

Be it known that I, JOHN W. EDMANDS, a citizen of the United States, residing at Newton Center, in the county of Middlesex 5 and State of Massachusetts, have invented certain new and useful Improvements in Railway Signal-Fusees, of which the following is a specification, reference being had therein to the accompanying drawing.

10 This invention relates to improvements in railway signal fusees, and the object of the invention is to provide a paper or fiber spike holding end for the fusee tube, the paper head being formed from the wall of the 15 paper tube, thus making the head integral with the tube and producing a one-piece spike holding fusee tube.

Heretofore the common practice of connecting spikes to fusee tubes is to provide 20 either a wood or metal plug of a size to fit in the end of the tube, and the wood-plug carry a separate spike or nail driven therein, and the metal-plug to have a separate nail cast therein, or in a few instances, the 25 spike is cast as a part of the plug. Whether a wood or metal plug is used, the commercial way of holding the plug within the end of the tube is by means of glue. In this instance the retention of the plug within the 30 end of the tube depends upon the glue or holding element, and in some cases, the plug has become separated from the fusee tube, thus leaving open the end of the tube for the burning composition to sift out, which 35 is objectional either in transportation or in use. Furthermore when the plug is lost or detached which forms a closure for one end of the tube, the fusee is not practically capable of use, and hence when the plug 40 closure becomes detached, the fusee is, from a practical point of view, destroyed.

My improvement provides a closure and a spike holding head for the fusee tube which is formed from the wall of the tube 45 itself, and therefore, can not become lost or detached, thus overcoming the objections to and disadvantage of the wood and metal plug heretofore used.

In the accompanying drawings:—Figure 50 1 is a perspective view of a fusee with my improved spike holding closure. Fig. 2 is a sectional view of Fig. 1. Figs. 3 and 4 show modifications of my improvement.

My improved fusee tube closure and spike 55 holder comprises a paper or fiber tube 1

which has one of its end walls crimped, folded and compressed into a suitable head 2. This head 2 is crimped, folded and compressed around the head-end 3 of the spike 4.

As shown in Fig. 2, the spike is provided 60 with a head 4 and with one or more ears or shoulders 5 which are formed by pinching the stem of the spike with a suitable tool.

In Fig. 3 I show a spike with its end 4^a made in the form of a hook, and in Fig. 4 65 4^b the head-end of the spike is made approximately S-shaped as shown at 4^b. The burning composition 6 is packed in the fusee in the usual manner.

In attaching the spike in my improved 70 spike holding head, the spike is supported by a suitable tool in position to have the extending end wall of the tube 1 crimped and folded inward and compressed around the head of the spike by a suitably constructed 75 rotating tool. The form of tool used is made the subject matter of a separate application, the invention here sought to be protected is the crimping and folding inward of one end of the wall of the fusee tube 80 around the head or inner end of the spike to connect the spike to the fusee tube. This crimping, folding inward, and pressing may be done either before or after the burning composition 6 has been placed in the tube. 85

There has been no attempt to show all of the various forms and modifications of the construction of the head-end of the spike because this may vary without departing from the spirit and scope of my improvement, and in fact, the inner end of the spike might be 90 headless and without any shoulders or projections, though preferably it is roughened, headed or twisted to more effectively lock it within the crimped, folded and compressed 95 head of the tube.

The illustrations herein are only a few of the mechanical expressions of the inventive idea here sought to be protected, and is not intended to prescribe the limits of the invention. I wish it also to be understood that the improvement is applicable to fireworks, 100 torches, etc., where a paper tube is used, and it is desired to attach a spike thereto for supporting the device in an upright position 105 while it is burning.

Having thus described my invention what I claim and desire to secure by Letters Patent is:

1. A device of the character described, 110

- comprising a fiber tube having one of its end walls crimped, folded and compressed inward around and embracing the inner end of a spike.
- 5 2. A device of the character described, comprising a fiber tube having one end wall crimped and folded inward and compressed, and a spike having its inner end embedded within the crimped, folded and compressed head.
- 10 3. A device of the character described, comprising a fiber tube and a spike for one end thereof, the end wall of the tube crimped and folded inward and compressed around the inner end of the spike, the inner end of said spike provided with lateral portions
- 15 also embedded in the crimped, folded and compressed head for uniting the spike thereto.
4. A device of the character described, comprising a fiber tube, a spike having a head, one end wall of the tube crimped and folded inward and compressed around the head of the spike in uniting the latter to the tube. 25
- In testimony whereof I hereunto affix my signature in the presence of two witnesses.
- JOHN W. EDMANDS.
